UNITED STATES PATENT OFFICE.

JOSEPH HOFFMAN, OF NEW YORK, N. Y., ASSIGNOR TO JOSEPH RECKENDORFER, OF SAME PLACE.

LEAD OR CRAYON HOLDER.

SPECIFICATION forming part of Letters Patent No. 267,528, dated November 14, 1882.

Application filed May 9, 1882. (No model.)

To all whom it may concern:

Be it known that I, JOSEPH HOFFMAN, of the city, county, and State of New York, have invented certain new and useful Improvements 5 in Lead or Crayon Holders, of which the following is a specification.

My invention relates to that kind of lead and crayon holder which is provided with a "stop-gage," arranged and operating to limit the extent to which the lead when released can drop or protrude from the pencil, as set forth in my application for Letters Patent of the United States already filed, and bearing the Serial No. 55,267; and it has particular reference to that 10 species of said holders, also described in my said application, in which is employed a stop-gage adapted to be projected beyond the point or tip of the holder, and when thus projected to extend into or across the path of the lead so as to intercept the point of the lead at a pre-determined distance beyond the end of the holder. In the holder shown and described in my said application (Serial No. 55,267) the stop-gage consists simply of a single tongue or strip 15 of light spring metal, bent or curved inwardly to some extent at its outer end, and formed or arranged so that this end, when the tongue is projected, will extend across the path which the lead would naturally follow in dropping 20 out from the holder. This device is simple and readily applied; but while it is effective in most cases, the lead, owing to the looseness with which it fits in the lead-containing tube, or from other causes, will occasionally pass to 25 one side of and beyond the point of the stop-gage. To remedy this objection, I have devised my present improvement, which consists in the employment of a stop-gage consisting of two or more tongues or strips so arranged 30 that when projected from the holder they will enter the path of the lead at the same distance from the tip or end of the holder, but from opposite sides, so that the lead, when it drops, no matter what may be its deviation from a 35 straight path, will meet and be arrested by one or the other of the tongues that constitute the stop-gage. The tongues when projected form in effect a loop, into which the lead falls, and by which it is held.

50 The nature of my improvement and the manner in which the same is or may be carried into effect will be readily understood by reference

to the accompanying drawings, in which I have represented my improvement applied to that kind of lead and crayon holder known in the 55 market as the "Automatic."

Figure 1 is a longitudinal central section of a holder embodying my improvement with the parts in their normal position. Fig. 2 is a like section with both the grasping-jaws carried 60 by the lead-containing tube and the stop-gage jaw protruded from the sheath. Fig. 3 is a side elevation of the holder. In all these figures the holder is represented as broken or divided transversely near the middle. 65

A is the tubular sheath or case, and a the tip or nozzle thereof.

The lead grasping or clamping device consists of spring expanding jaws b, attached to or forming part of the longitudinally-movable 70 tube B, the rear end of which projects beyond the sheath, and is provided with a flange or collar, c, between which and the sheath is confined the comparatively-stiff spiral retracting-spring d, which acts to retract the jaws into 75 the nozzle, and to thus cause them to close. The extent to which the tube can be retracted is limited by the lip or projection e upon it. The pencil thus far is similar in its general characteristics to the Automatic. 80

Within tube B is another longitudinally-movable tube, C, whose rear end extends beyond tube B, and is surmounted by a cap, D, which serves as the "pressure-cap," and between the head of the cap and flange c is confined a second spring, f, which is lighter and more easily compressed than spring d, the result of this arrangement being that when the cap D is pressed the tube C will first move forward alone for a certain distance, and then 90 the two tubes will move forward together, and when the cap afterward is relieved of pressure the two tubes will move back together until lip e brings up against the sheath, and then the reaction of the still compressed 95 lighter spring f will still further move back the inner tube to its first position. I employ the inner tube both as the stop-gage carrier and as the lead-receiver; but it will be understood that it is not indispensable to employ a 100 tube, as shown. I may use instead strips or pieces of other form, and it is not essential that the stop-gage carrier should work within the lead-containing tube. The arrangement

shown, however, is preferred, as being on the whole the most convenient and easy of adaptation to existing forms of lead and crayon holders.

5 The stop-gage shown in the drawings consists of two narrow tongues or strips of light spring metal, *g*, which are placed diametrically opposite one another on the front end of the carrier-tube *C*, and are of such length that 10 their front ends are normally flush or even with the front ends of the jaws *b*, and they are so placed as to be situated in the slots or intervals which separate these two jaws. Their outer ends are bent or curved inwardly to 15 some extent, and are preferably so formed as to have a "set," which will cause them normally to approach one another just a little closer than the thickness of the lead. I also prefer to provide each strip or tongue on its 20 outer face with a cam-projection or swell, which, when the tongues are projected to nearly their full extent from the holder, will, by coming in contact with the inner surface of the tapering tip or nozzle *a*, cause the tongues to close 25 together or approach one another, so as to bring their opposite outer ends in contact, or nearly so, and thus form a loop into which the released lead can drop. The cam-projection or swell is obtained in this instance by bending the tongue or strip outwardly at the point *h* before it is tempered. The tongues, when released from contact of their cams, expand 30 or spread apart to their normal position.

The foregoing details of construction of the 35 tongues are niceties but not necessities. They may manifestly be arranged and operated in other ways so as to be caused to project into or across the path of the lead at a predetermined distance in front of the holder.

40 The operation is as follows: When the pressure-cap is pushed forward the first effect is to advance the carrier-tube *C* so as to move the stop-gage tongues to a position in advance of the jaws, the jaws *b* still remaining unmoved and closed. Further pressure causes the jaws and stop-gage, still occupying the same relative position, to move forward until the jaws expand, and the lead *x* can then drop out from the pencil into the loop formed by the tongues 45 *g*, that constitute the stop-gage, as shown in Fig. 2. Pressure is now removed from the cap *D*, and the two tubes *B* *C* move back together until the jaws *b* close tight upon the lead, which renders the tube *B* incapable of further movement, after which the carrier-tube *C* moves 50 still farther back, and in so doing retracts the stop-gage tongues to their original position.

It is desirable to have the stop-gage tongues made of tempered metal, and for this purpose 55 I prefer to form them separately from the carrier-tube, making them part of a split annulus, *g'*. After they are tempered the annulus is fitted around and closed on the front end of the carrier-tube and is held there by lips *i* on the tube, which pass through slits in the annulus, and are then swaged down.

It is manifest that it is not necessary to ar-

range the two tongues which constitute the stop-gage diametrically opposite one another, although this arrangement is on the whole 70 the most desirable, and is also convenient in the respect that it permits them to lie in the spaces which intervene between the two grasping-jaws *b*. It is also manifest that more than two tongues or strips can be employed, if de- 75 sired.

I also remark that the feature herein described and illustrated, of a cam-projection or swell on the stop-gage adapted to be operated on by the sheath so as to cause the outer end 80 of the stop-gage, when it is moved forward, to project into the path of the lead is applicable not only to the stop-gage herein described, but also to one composed of a single tongue or strip—*e.g.*, supposing only one tongue or strip 85 *g* were used instead of two or more. The advantage gained by this feature is that I am thereby enabled to give the spring tongue or strip such a set as will cause it to tend to move, when not under control of its cam, far 90 enough away from the lead to avoid injurious frictional contact therewith in returning from its projected to its normal position.

What I claim herein as of my invention is—

1. In a lead or crayon holder, the combination, with a lead-containing case or sheath and a lead clamping or grasping and releasing mechanism, of a movable stop-gage composed of two or more oppositely-placed strips or tongues adapted to be projected beyond the 95 point or tip of the holder, and when thus projected to extend into or across the path of the lead at a predetermined distance from the end of the holder, substantially as and for the purposes hereinbefore set forth. 100

2. The combination, with the sheath, the grasping-jaws, and the longitudinally-movable tube carrying said jaws, of the independently-movable stop-gage carrier, and the stop-gage 110 consisting of two oppositely-placed bent or hook-like spring strips or tongues located in the spaces or intervals between said jaws, and adapted, when projected from the pencil, to extend into or across the path of the pencil at a predetermined distance in front of the jaws, 115 substantially as and for the purposes hereinbefore set forth.

3. In a lead or crayon holder, the combination, with the lead grasping and releasing mechanism, of a longitudinally-movable stop-gage, adapted to be projected from and retracted into the holder, and provided with a cam or swell acted on by the holder when the stop-gage moves forward, to compel the outer end of said gage to move into or across the 120 path of the lead, substantially as and for the purposes hereinbefore set forth.

In testimony whereof I have hereunto set my hand this 27th day of March, 1882.

JOSEPH HOFFMAN.
